UNITED STATES PATENT OFFICE.

NEAL T. GOOLSBY, OF FRESNO, CALIFORNIA, ASSIGNOR OF ONE-HALF TO HAROLD DUNKLEY, OF FRESNO, CALIFORNIA.

ATTACHMENT FOR SUCKER RODS.

Application filed September 27, 1928. Serial No. 308,866.

This invention relates to an attachment for use in connection with sucker rods of oil wells or the like, the primary object of the invention being to provide means for preventing 5 rotary movement of the sucker rod, thereby insuring against the sucker rod sections becoming disconnected.

A further object of the invention is to provide means to insure the working valve cups 10 of the well seating in one position at all times, thereby equalizing the wear on the cups.

Another object of the invention is to provide a device of this character which may be readily and easily secured in the usual well 15 construction, without making extensive alterations to install the attachment.

With the foregoing and other objects in view which will appear as the description proceeds, the invention resides in the combination and arrangement of parts and in the 20 details of construction hereinafter described and claimed, it being understood that changes in the precise embodiment of the invention herein disclosed, may be made within the 25 scope of what is claimed, without departing from the spirit of the invention.

Referring to the drawing:

Figure 1 is a longitudinal sectional view 30 through well tubing, illustrating the application of the invention.

Figure 2 is a sectional view through the sucker rod attachment.

Figure 3 is a side elevational view thereof.

Figure 4 is a transverse sectional view 35 through the attachment.

Figure 5 is a sectional view taken on line 5-5 of Figure 1.

Figure 6 is a sectional view taken on line 6-6 of Figure 1.

40 Referring to the drawing in detail, the reference character 5 designates one end of the pump barrel which is threaded to receive the threaded extremity 6 of the barrel or attachment, which is indicated generally by the reference character 7.

The upper end of the barrel 7 is threaded to connect with the first joint of the well tubing, the well tubing being indicated by the reference character 8. Formed in the inner 50 surface of the barrel 7, and disposed opposite to each other, are grooves 9 which grooves are of lengths equal to the length of the stroke of the sucker rod, and are of widths to accommodate the guiding blades 10 of the attach-

ment, the grooves acting as guideways for the 55 blades. The ends of these grooves are slightly inclined as at 11 so that the device may be withdrawn should it be desired to make repairs, or disassemble the sucker rod.

Forming an important part of the attachment is a body portion 12 having a threaded extension 13 to be fitted in the threaded end of the sucker rod section 14, while at the upper end of the body portion 12 is a threaded bore to accommodate the threaded extremity 15 of 60 65 the sucker rod section 16.

Cut out portions are formed in the sides of the body portion 12 and accommodate the blades 10 that are held against displacement by means of the pins 18 that move in elongated openings 19 there being provided a coiled spring 20 fitted in an opening of the body portion 12, the ends of the coiled spring being seated in openings of the blades 10. 70

Thus it will be obvious that movement of 75 the blades 10 with respect to the body portion 12, will be permitted at all times, the action of the spring 20 being such as to normally urge the blades into close engagement with the walls of the grooves.

As the sucker rod is reciprocated vertically while in operation, it will be seen that all 80 rotary movement of the sucker rod is prevented to the end that the possibilities of the sections of the sucker rod becoming disconnected are eliminated.

I claim:

1. In combination with the well tubing and sucker rod of a pump, a barrel secured between sections of the tubing and having 90 grooves formed therein, a body portion secured between sections of the sucker rod, movable blades supported by the body portion and movable in the grooves, and means for normally urging the blades laterally.

2. In combination with the well tubing and sucker rod of a pump, an attachment including a barrel secured between sections of the well tubing, said barrel having grooves, a body portion secured between sections of the sucker rod, and resilient members extending from the body portion and movable in the grooves to guide the sucker rod while in operation.

3. In combination with the well tubing and sucker rod of a pump, an attachment including a barrel secured between sections of the well tubing, a body portion secured between

sections of the sucker rod, spring pressed blades extending from the body portion, and said barrel having grooves to receive the blades to prevent rotary movement of the sucker rod.

4. In combination with the well tubing and sucker rod of a pump, an attachment including a barrel secured between sections of the well tubing, said barrel having grooves, a body portion secured between sections of the sucker rod, said body portion having lateral cut out portions, spring pressed blades within the cut out portions, said blades being positioned in the grooves to guide the body por-

tion and sucker rod to which the body portion is connected.

5. In combination with the well tubing and sucker rod of a pump, a barrel positioned between sections of the well tubing, a body portion secured between sections of the sucker rod, and operating within the barrel, said barrel having grooves, and laterally extended members on the body portion and operating in the grooves to prevent rotary movement of the sucker rod.

In testimony that I claim the foregoing as my own, I have hereto affixed my signature.

NEAL T. GOOLSBY.
